VACUUM CLEANER ACCESSORY RACK

Richard D. Dilyard, Wooster, Ohio, assignor to Rubbermaid Incorporated, Wooster, Ohio

Filed Oct. 20, 1972, Ser. No. 300,775

Term of patent 7 years

Int. Cl. D6—04

U.S. Cl. D6—136

FIG. 1

FIG. 3

FIG. 1 is a front perspective view of a vacuum cleaner accessory rack embodying my new design.

FIG. 2 is a side elevation thereof.

FIG. 3 is a vertical sectional view on line 3-3 of FIG. 1.

The side opposite to that shown in FIG. 2 is a mirror image thereof.

I claim:

The ornamental design for a vacuum cleaner accessory rack, as shown and described.
